UNITED STATES PATENT OFFICE.

JOHN E. NAUDAIN, OF SPARROWS POINT, MARYLAND.

METAL-BENDING MACHINE.

Application filed November 26, 1926. Serial No. 150,725.

This invention relates to improvements in metal bending machines and has particular reference to a machine wherein a plurality of independently adjustable formers are employed around which the bending operation takes place in conjunction with a hand-operated sweep bar and head to effect the bending.

The object of the invention is to provide a simple and easily operated machine embodying two formers for right or left hand bending and a head so located with respect to the two formers that it may be swung in conjunction with either former to effect the bending desired.

The invention is illustrated in the accompanying drawing, wherein,—

Fig. 1 shows the complete machine in side elevation;

Fig. 2 illustrates the same in top view;

Fig. 3 shows the two formers and the head in plan view, with a bar of metal arranged between the formers and the head and in readiness for a left-hand bending operation;

Fig. 4 illustrates the same parts but with the head and bar moved to the left at the end of the bending operation;

Fig. 5 shows a cross-sectional detail through the guide-block which carries one of the formers, the section being taken on the line 5—5 of Fig. 2; and

Fig. 6 illustrates a cross-sectional detail through the center of the table showing the pivot of the head mounted therein, and it also shows the two right-angle faces of the head in side elevation.

Referring to the drawings, the numeral 10 designates a base having a central vertical column or pedestal 11 which carries a circular horizontal flange 12 at its upper end.

On top of the circular flange 12 of the pedestal there is a flat bed 13 having two extensions 14 and 15, and which extensions are provided with guideways 16 and 17. These extensions and guideways are disposed on lines at right angles with respect to each other.

Each guideway is provided with horizontal guide-flanges 18 at opposite sides thereof, and the outer ends of the guideways are closed by cross-bars 19 which are held in place by stud-bolts 20.

A screw-shaft 21 extends horizontally into the guideway 16 and a similar screw-shaft

22 extends into the guideway 17. These screw-shafts have their outer ends extending through the cross-bars 19 in which they have bearing, and on the outer end of screw-shaft 21, there is a hand-crank 23 by which said shaft 21 may be rotated in either direction, while a similar crank 24 is provided on the outer end of shaft 22.

At the inner ends of the two right-angle extensions 14 and 15 the flat bed 13 is provided on its under side with a downwardly-extending tubular boss 25 which latter projects down into the pedestal 11, as shown in Fig. 6, and this boss has a vertical bearing-opening 27 with an enlarged annular recess 26 around its upper end and in the top surface of the bed for a purpose which will presently be explained.

In the guideway 16 there is mounted a movable block 28, while in the guideway 17 there is a similar block 29. Each block has guide-grooves 30 in its opposite sides to receive the guide-flanges 18, so as to slide thereon, and these blocks 28 and 29 have screw-threaded passages 31 extending longitudinally therethrough so that the screw-shafts 21 and 22 may extend lengthwise through the blocks.

The shafts 21 and 22 are held in the cross-bars 19 against longitudinal movement so that when either of them is rotated, the block 28 or 29 engaging that shaft will be moved forward or back in a horizontal plane according to the direction the shaft is rotated.

On the block 28 there is an upright former 32 which extends above the bed 13, while the block 29 has a similar upright former 33. Each upright former has a dovetail shaped projection 34 on its vertical face, and to the former 32 there is attached a former-block 35, while to the former 33 there is attached a former-block 36.

The former blocks 35 and 36 each have dovetail shaped grooves therein so as to fit and slide onto the dovetailed shaped projections 34, and by means of this construction, one former block may readily be removed and replaced by another, either of the same exterior shape or of a slightly different exterior shape to suit the particular bending work to be done.

The structure is such that when the two guide-blocks 28 and 29 are moved toward the center of the column to the full limit of their movement, their flat vertical faces

will abut, but either of them may be moved independently of the other.

In addition to the two guide-blocks, formers, and former-blocks, I also employ a bender head which will now be described, reference being made to Figs. 2, 3, 4, and 6.

The bender-head has a circular flange 37 from which there depends a central pivot-post 38. This post snugly fits and extends 10 down into the vertical bearing-opening 27 through the boss 25, and the circular plate 37 seats in the annular recess 26, in the top surface of the bed between the right-angle extensions, as shown in Fig. 6.

15 Extending vertically from the circular flange 37 is a bender-head proper 39, which latter has two right-angled faces 40 and 41, which faces extend radially with respect to the central vertical axis of the pivot-post 38.

20 A side lug or enlargement 42 extends laterally and horizontally from the head 39, and this lug has a horizontally-extending U-shaped recess 43 in its upper side. An operating bar 44 has its end 45 extending 25 into the recess 43 of the head, and a bolt 46 extends through the lug of the head and also through the bar-end to hold the latter in place.

The operation of the machine briefly is as 30 follows:

Presuming a bar of metal 47 is to be bent into a right-angle form with the turn or bend extending in a left-hand direction.

The bender block 29 will be left in its innermost position in the guideway 17, and the head 39 will be swung around until its face 41 seats against the vertical face of the block 29, as shown in Fig. 3. When the head 39 and block 29 are in this position, the vertical bending face 40 of the head will be 35 in alinement with the former-block 36 of block 29.

The bar 47 to be bent is then laid on the bed 13, so as to extend diametrically across 40 the circular plate 37 of the bender-head, and the block 28 is then moved inwardly in the guideway 16 until it clamps the bar 47 against the former-block 36.

This operation leaves the blocks 28, 35 45 set forward from the center of the bender-head plate 37 a distance equal to the thickness of the bar 47 that is to be bent, as shown in Fig. 3, and everything is then set for the actual bending operation.

50 The operating bar 44 is then grasped by

hand and pushed horizontally, causing the head with its flat face 40 to swing in the direction of the arrows in Fig. 3, and in doing so, the bar 47 will be bent around the former-block 35 until it is forced against the sides of said blocks 28 and 35 as shown in Fig. 4.

Having thus completed the operation of bending the bar 47, the block 28 may now be retracted by moving the same outwardly 65 in the guideway 16 and the bent bar may then be removed.

The adjustment of the parts is rapidly effected to position the bar to be bent, and the bending and removal of the bent bar is 70 quickly accomplished.

Having described my invention, I claim,—

1. In a machine for bending metal bars, the combination with a pedestal, of a bed mounted on the pedestal and having two portions which extend at right angles with respect to each other, said bed also having a tubular boss depending from its under side into the pedestal, each of the said two right-angled extensions of the bed having 75 guideways with blocks therein, a former carried by and extending vertically above each of said blocks and each former being provided with a detachable former-block, a bender-head pivotally engaging the 80 tubular depending boss and extending down into the pedestal, and means for adjusting the blocks in the guideways of the right-angled extensions.

2. In a machine for bending metal bars, 90 the combination with a pedestal, of a bed mounted on the pedestal and having two portions which extend at right angles with respect to each other, said bed also having a tubular boss depending from its under side into the pedestal, each of the said two right-angled extensions of the bed having 95 guideways with blocks therein, a former carried by and extending vertically above each of said blocks, a former-block for each former, said blocks and formers having dovetail connections whereby the blocks may be detached, means for adjusting the blocks in the guideways of the right-angled extensions, and a bender head having a post 100 which passes down into the tubular boss of the bed whereby to pivotally mount the same centrally over the pedestal.

In testimony whereof I affix my signature.
JOHN E. NAUDAIN.
